UNITED STATES PATENT OFFICE.

MORRIS O. HENDERSON, OF STORY CITY, IOWA.

DUMPING DEVICE AND PROCESS.

1,415,640.

Specification of Letters Patent.

Patented May 9, 1922.

Application filed August 10, 1920. Serial No. 402,660.

To all whom it may concern:

Be it known that I, MORRIS O. HENDERSON, a citizen of the United States, and a resident of Story City, in the county of 5 Hamilton and State of Iowa, have invented a certain new and useful Dumping Device and Process, of which the following is a specification.

The object of my invention is to provide 10 a dumping device of simple, durable and inexpensive construction for sand, gravel and dirt.

More particularly it is my object to provide a dumping device, including an engine 15 mounted to swing on a pivot and to provide in connection therewith a dumping structure, comprising an inclined track or floor, a hopper, and a movable door therefore, together with mechanism for connecting the 20 engine and the dumping device, and a slip or scraper in such manner that the greater part of the pull on the dump is parallel with the lines of the braces thereof.

Still a further object is to provide such 25 a device, having a dump with a pulley located directly above the scraper at the time the scraper is discharged.

An additional object is to provide in such 30 a structure, a novel means for connecting the scraper with the operating mechanism.

Still a further object is to provide such a device having a dumping and hoisting 35 mechanism, and means for varying the line of travel of a slip or scraper that is adapted to travel between the hoisting and dumping devices.

Still another object is to provide in such a device mechanism for varying the line of 40 travel of a slip or scraper so that a great area may be worked upon by the slip without the necessity of moving either the hoisting or dumping mechanisms.

With these and other objects in view, my 45 invention consists in the construction, arrangement and combination of the various parts of my device, whereby the objects contemplated are attained, as hereinafter more fully set forth, pointed out in my claims, and illustrated in the accompanying drawings, in which:

Figure 1 shows a side elevation of a loading device embodying my invention.

Figure 2 shows a front elevation of the same, the hopper being removed.

Figure 3 shows a detail, sectional view 55 taken on the line 3—3 of Figure 1.

Figure 4 shows a side elevation of another form of the scraper.

Figure 5 shows a diagrammatic view, illustrating the arrangement of the engine 60 and dump in a sand pit or the like.

Figure 6 is a top, plan view of my dumping device showing how the line of travel of the slip may be varied, the hopper at the upper end of the runway and the handle on 65 the scraper being omitted to permit better illustration of the other parts.

Figure 7 is a detail view of a portion of the mechanism for varying the line of travel of the slip. 70

In the accompanying drawings, I have used the reference numeral 10 to indicate generally a support for a power unit, such as a gasoline engine 11.

The base 12 of the engine is pivotally supported for horizontal rotation on the support 10 by means of an upright shaft or post 13. Supported on the base 12 is a suitable hoisting mechanism 14, including drums and suitable connecting parts of ordinary construction, which in themselves form no part of my invention. 75

I provide in connection with the engine, a dumping structure, comprising spaced uprights 15. The uprights 15 are connected 85 at their upper ends by a cross member 16. Connected with the lower ends of the uprights 15 and extending rearwardly therefrom and inclined away from each other are frame members 17. 90

The frame members 17 and 15 are supported on traction devices, such as skids 18. In the ends of the skids 18 are rings or the like 19 to which a tractor or team of horses may be connected for moving the dump 95 from place to place.

Extending from the braces 15 approximately midway of their height downwardly and rearwardly to the rear skid 18 are brace frame members 20. Connecting the rear 100 ends of the members 17 and the upper portions of the members 15 are brace members 21. Connected with the upper portions of the members 15 and inclined downwardly and outwardly therefrom to the forward 105 skid 18 are frame members 22.

Vertical supporting members 22^a are provided which are fixed to the frame members

17 and to brace members 21. The supports 22^a are bolted to the cross bar 22^b which is fixed to the members 20 and supports the floor structure hereafter described.

5 Supported on the frame members 20 is an inclined runway or floor or the like 23, extending from the rear skid upwardly to the central portions of the members 15, and thence inclined downwardly and forwardly, 10 as at 24. The portion 24 forms the bottom of a hopper, having the sides 25. Connected with the upper portions of the forward ends of the sides 25 by hinges 26 is a closure member 27. A spring clip catch device 28 is secured to the member 24 and adapted to lock the closure device 27 in closed position.

I have provided in connection with the engine and the dump a slip or scraper 29, having at its rear portion the raised side 20 members 30. Extending rearwardly from the slip 29 is a handle 31, which may be bent to different positions. The handle is of such material and so attached that it may be bent by manual operation. Such bending, is, 25 of course, done only infrequently. A brace 32 is connected with the bottom of the slip 29 and with a U bolt clamp 33 on the arms of which are nuts 34.

By loosening the nuts 34 and bending the 30 handle 31 to different positions, and then tightening the nuts 34, the handle may be locked in various adjusted positions.

The sides of the slip 29 are each provided with a series of holes 35 to receive bolts 36 35 and 37. Connected with the bolt 36 is a forwardly extending bail 38, at the forward central portion of which is mounted a pulley 39.

Extended rearwardly from the slip and 40 pivotally mounted on the bolts 36 is a rear bail 40. Connected with each bolt 37 is a brace 41 extending forwardly and inclined away from the wall of the slip and mounted on the adjacent bolt 36 between the arms of 45 the bails 38 and 40, as clearly illustrated in Figure 3.

Secured to the upper part of the dump approximately directly above and slightly forwardly of the bend in the floor or the like 50 23 is a pulley frame 42, in which is mounted a pulley 43. Connected with the pulley frame 42 is a rope or cable or the like 44, which extends from the frame 42 around the pulley 39, thence upwardly and around 55 the pulley 43 and thence to the hoisting mechanism 14.

The placing of the pulley a short distance forwardly of the bend in the floor will make it possible to easily dump the load from the 60 slip.

Connected with the bail 40 is a cable 45, which is connected to the hoisting mechanism 14.

In Figure 4, I have shown a slightly dif-

ferent form of slip 46, having at its rear portion, an upwardly extending back member 47. Connected with the sides of the slip 46 is a suitable bail 48, on which is a pulley 49 around which the cable 44 may be extended.

Connected with the rear part of the slip 46 are handles 50. Connected with the sides of the slip 46 forwardly of the points of connection of the bail 48 are cables 51, which are connected with the cable 45. The 75 handles 50 are connected with the side walls of the slip 46 at such points as to form stops for limiting the rearward, swinging movement of the bail 48.

In the practical use of my improved dumping device, the dump and the engine are properly located and the engine may then be run for dragging the slip toward the dump. The slip is first pulled away from the dump by means of the cable 45, to position near 80 the engine.

The engineer can then hold the handle of the slip, and after the engine has been started for loading the slip, he may then release the handles and remain near the engine 90 for controlling it.

The slip is drawn toward the dump and will travel up the floor 23 until it stands above the bend in the floor 23 and moves to position where the greater part of the load 95 is slightly forwardly of the bend, when the slip will automatically move to dumping position.

It will be noted that the bolts 36 are located rearwardly of the center of gravity 100 of the loaded slip, so that when the slip is in position for discharging the load will be forwardly of the bolts 36 and the pull upwardly on the bolts 36 will tend to dump the load into the hopper.

For handling different kinds of dirt and gravel the bolts 36 and 37 are adjusted rearwardly or forwardly, as desired, and mounted in different holes 35.

It will be noted that by connecting the 110 rope or cable 45 with the frame 42 and then extending it around the pulley 39 or 49, as the case may be, and thence around the pulley 42, the greater part of the pull on the dump will be in line as nearly as possible 115 parallel with the brace members 20 and also the brace members 21, so that with this arrangement, there is less tendency to upset the dump than is the case where the rope is connected with the bail 38 and thence extended around the pulley 42 to the hoisting mechanism.

Attention is called to the advantage of leaving the engine at the center of a circle, and the arranging of the dump at the outside of the circle and mounting it on skids and traction devices, whereby it may be moved around the circle.

It will thus be seen that the great amount of the load is taken at the outside of the circle nearest the point of discharge.

It will also be noted by the arrangement just mentioned that the slip at the time of loading is near the engine, so that one man can handle the slip and also operate the engine.

The points of connection of the bail 38 with the slip 29 may be varied by mounting the bolts 36 in different holes 35 for accommodating the device to different kinds of dirt and sand and gravel, for insuring the automatic dumping, when the slip is drawn to the upper portion of the floor 23.

An extension 52 may be provided at the lower end of the floor 23 for use after a hole has been dug between the engine and the dump.

It will be noted that the parts are so arranged in the modified form of the slip, shown in Figure 4, that when the dumping action occurs and the slip tilts forwardly at the upper portion of the floor 23, the handles 50 will serve as stops to engage the arms of the bail 48 for holding the slip in dumping position.

It will also be noted that on account of the locating of the points of connection between the bail 48 and the slip 46 rearwardly of the points of connection of the cables 51 with the slip 46, when the slip reaches its upper position at the upper portion of the forward portion 23, the cable 45 may be held taut and the cable 44 pulled for raising the rear end of the slip and insuring proper dumping or discharging action.

In Figures 6 and 7 I have shown mechanism for varying the line of travel of the slip relative to the hoisting and dumping mechanism.

Fixed to the base 10 of the hoisting mechanism is a bracket or supporting member 53 in which is pivotally mounted the arm 54 on the pivot 55. The pivot 55 is received within the opening in the support 53.

A plate 56 is fixed to the pivot 55 and is bolted to the arm 54 by means of the bolts 57. This forms a substantial rigid bearing.

Extending upwardly from the plate 56 is the short shaft 58 on which is rotatably mounted a pulley wheel 59. On the forwardly extending end of the arm 54 is the pulley wheel 60 mounted on the shaft 61.

The return cable 45 which is fixed to the hoisting apparatus 14 and to the scraper or slip 29 is passed around the pulley wheels 60 and 59, as illustrated in Figures 6 and 7 of the drawings.

Fixed to the base 10 of the hoisting apparatus on either side thereof are the hook members 62, to which is fastened the cable 63.

Pivoted on the shaft 61 is the yoke 64 which is fixed to the cable 63. From the

construction of the parts just described it will be seen that lengthening or shortening the cables 63 will permit movement of the arm 54 on its pivot.

When the cable 63 is lengthened the arms 70 54 will be moved to the position shown in dotted lines on Figure 6 of the drawings. By permitting such movement the line of travel of the slip 29 will be varied so that earth or sand may be engaged for a substantially great area on either side of a direct line between the hoisting and dumping mechanisms.

When the arm 54 is swung substantially a half revolution, the cable 63 is fastened to 80 the hook member 62 on the opposite side of the base 10 of the hoisting mechanism. It is then necessary to remove the cable 45 and turn it over so that it will work on the pulley wheels 59 and 60, even though the 85 arm has been swung substantially 180 degrees.

The advantages of this device can readily be seen because the necessity of moving either the hoisting or dumping devices is 90 practically reduced to a minimum, while material and a wide area may be loaded.

Some changes may be made in the construction and arrangement of the various parts of my device, without departing from 95 the real spirit and purpose of my invention, and it is my intention to cover by my claims, any modified forms of structure, or use of mechanical equivalents, which may be reasonably included within their scope. 100

I claim as my invention:

1. In a machine of the class described, a base, a hoisting mechanism pivotally supported thereon, a dump having upright members, rearwardly inclined brace members, an inclined floor having at its upper end a downwardly inclined extension, side walls on said extension, a pulley supported at the upper part of said dump above the highest part of said inclined floor, a slip, 110 a bail connected with said slip, a pulley on said bail, a rope connected with said dump and extended around said last pulley, thence around said first pulley and thence to said hoisting mechanism, a draft device connected with said slip forwardly of the points of connection of said bail, and a handle on said slip adapted to serve as a stop for said bail.

2. In a machine of the class described, 120 a base, a hoisting mechanism pivotally mounted thereon, a dump device, said dump device comprising uprights, braces extending rearwardly from the upper portions of said uprights, an inclined floor, a hopper at 125 the upper end of said inclined floor, a pulley above the upper rear end of said hopper, a slip having a bail, a pulley on said bail, and a cable connected with the upper part of said dump device extended around said last 130

- 5 pulley and thence around said first pulley and thence to said hoisting mechanism, whereby the greater pull on said dump device is substantially parallel with the braces 5 thereof.
- 10 3. In a machine of the class described, a base, a hoisting mechanism pivotally mounted thereon, a dump device, said dump device comprising uprights, braces extending rearwardly from the upper portions of said uprights, an inclined floor, a hopper at the upper end of said inclined floor, a pulley above the upper rear end of said hopper, a slip having a bail, a pulley on said bail, and a cable connected with the upper part of said dump device extended around said last pulley and thence around said first pulley and thence to said hoisting mechanism, whereby the greater pull on said dump 20 device is substantially parallel with the braces thereof, said slip having a bendable handle, a brace connected with said slip, and means for locking said brace to said handle in different positions thereon.
- 25 4. In a device of the class described, a base, a hoisting mechanism pivotally mounted thereon, a dumping device adapted to be moved around said hoisting device, said dumping device consisting of uprights, braces extending rearwardly and downwardly from the upper portion thereof, an inclined floor, a hopper at the upper end of said inclined floor, a pulley on the upper portion of said dumping device, a slip, a bail thereon, having a pulley, a cable secured to said dumping device near the upper part thereof and extended around said last pulley, thence around said first pulley, and thence to said hoisting device, whereby 35 40 when said dumping device is moved around the hoisting device the hoisting device will be automatically adjusted to certain positions with relation to the dumping device.
- 45 5. In a loading device, a base, a hoisting mechanism pivotally mounted thereon, a dumping device adapted to be moved around said hoisting device, said dumping device including an inclined floor and a hopper, a slip, a cable operatively connected with said hoisting mechanism and said slip for moving the slip towards or from the dumping device and an arm pivotally mounted on said base forwardly of said hoisting mechanism for varying the line of travel of the slip without the necessity of moving either 50 55 the hoisting or dumping device.
6. In a loading device, a base, a hoisting mechanism pivotally mounted thereon, a dumping device adapted to be moved around said hoisting device, said dumping device including an inclined floor and a hopper, a slip, a cable operatively connected with said hoisting mechanism and said slip for moving the slip towards or from the dumping device and means for varying the 60 65 line of travel of said slip, said means including a member supported on said base capable of pivotal movement in a horizontal plane, a pair of pulley wheels mounted on said member, one near the forward end and one near the rear end of said member, the cable passing around each of said pulley wheels for the purposes stated.
7. In a device of the class described, a supporting frame, a hoisting mechanism 75 pivotally supported thereon including an engine or the like and cables, a dumping structure spaced from said frame and adapted to be moved in a circle around said frame, a slip connected with said cables, one of said cables being connected with said dump device.
8. In a device of the class described, a supporting frame, a hoisting mechanism pivotally supported thereon including an engine or the like and cables, a dumping structure spaced from said frame and adapted to be moved in a circle around said frame, a slip connected with said cables, one of said cables being connected with said dump device, an adjustable guide element for one of said cables, by the adjustment of which, the travel of the slip may be varied.

Des Moines, Iowa, August 5, 1920.

MORRIS O. HENDERSON.
